COMBINED KNIFE SHARPENER AND MEAT CARVING FORK

Rinzy Nocero, 181 73rd St., Brooklyn, N.Y. 11209
Filed May 25, 1971, Ser. No. 146,857

Term of patent 14 years

Int. Cl. D7—04

U.S. Cl. D44—29

FIG. 1 is a front perspective view of the combined knife sharpener and meat carving fork.

FIG. 2 is a side elevation thereof.

FIG. 3 is a rear elevation thereof.

FIG. 4 is a handle-end view thereof.

FIG. 5 is a sectional view on an enlarged scale taken along line 5—5 in FIG. 3.

I claim:

The ornamental design for a combined knife sharpener and meat carving fork, as shown.
